UNITED STATES PATENT OFFICE.

JAMES F. CORVIN, OF CHICAGO, ILLINOIS, ASSIGNOR TO McCORD AND COMPANY, OF CHICAGO, ILLINOIS, A CORPORATION OF NEW JERSEY.

PROCESS OF PRODUCING FLUID-CONDUITS IN CASTINGS.

1,234,878.

Specification of Letters Patent.

Patented July 31, 1917.

Application filed September 15, 1913. Serial No. 789,797.

To all whom it may concern:

Be it known that I, JAMES F. CORVIN, a citizen of the United States, residing at Chicago, in the county of Cook and State 5 of Illinois, have invented certain new and useful Improvements in Processes of Producing Fluid-Conduits in Castings; and I do hereby declare the following to be a full, clear, and exact description of the invention, 10 such as will enable others skilled in the art to which it appertains to make and use the same.

In lubricating systems and in various other different devices, it has long been the 15 common practice to form oil or fluid conduits by boring long and frequently very small holes in castings forming part of the apparatus or device. These oil or fluid conduits often require a very complicated system of boring intersecting holes from various 20 different points and at various different angles, and an elaborate plugging of certain of the holes. Frequently, also, it is desirable to extend these tortuous conduits 25 on such lines that they cannot possibly be bored. Sometimes, these tortuous conduits may be produced by destructible cores, but where conduits are of small diameter, this 30 is difficult and often impossible. Furthermore the bored holes will not have the desired smooth walls.

My invention is directed to an extremely simple and efficient process for forming these oil or fluid conduits exactly on desired lines, whether simple or intricate and of the exact desired size, independently of the boring operation and without the use of destructible temporary cores. The desired results are accomplished by the use of a tube 40 having the lines or form of the desired conduit, which tube is cast into the casting in which the conduit is to be formed. This conduit forming tube should have a higher fusibility than the casting in which it is embedded, and usually would be a seamless steel tube. It is placed in the wall and used after the manner of a core, but when the metal is cast around the same, it becomes a permanent integral part of the casting. 45 When valves are to be used in connection with the conduit, valve seats may be formed by boring holes in the casting which intersect and cut through the conduit forming tube at desired points.

50 The invention resides both in the process

above stated, and in the product resulting from the process.

In the accompanying drawings which illustrate the invention, like characters indicate like parts throughout the several 60 views.

Referring to the drawings:

Figure 1 is a sectional view showing a casting with the conduit forming tube cast into the same and with the cores applied to 65 the projecting ends of the tube for the purpose of supporting the tube in the sand during the process of molding; and

Fig. 2 is a view corresponding to Fig. 1, but showing the casting completed and 70 formed with valve seats that intersect the conduit and provided therein with valves for coöperation with the said conduit.

The numeral 1 indicates a casting, which, in this particular instance, happens to be a 75 casting of a type employed in certain lubricating systems, not necessary for the purposes of this case to particularly consider. The numeral 2 indicates a seamless steel-tube bent into the form of the oil conduit which 80 it is desired to form in the said casting. The said tube, as shown, having several rectangular bends. The ends of the tube 2 are embedded in tube anchors 3. Prior to forming the casting 1 in the mold provided therefor, 85 the tube 2 is supported after the manner of a core within the mold cavity, by means of anchors 3 embedded in the sand in the well known way. The molten material is then pored into the mold cavity and all of that 90 portion of the conduit forming tube which is exposed within the mold cavity, will be embedded within the casting and will become a permanent integral part thereof.

Fig. 1 shows the casting and tube as they 95 would appear when taken from the mold and before the tube supporting cores 3 have been removed from the projecting ends of the tube.

Fig. 2 shows the completed casting 100 equipped with valves required for one particular purpose. By reference thereto, it will be noted that one valve seat for the ball valve 4 is formed by boring a hole 5 into the casting 1 and thereby cutting away a 105 portion of the left hand end of the tube 2. The outer end of the hole 5 is closed by a plug 6. Another valve seat for ball valves 7 is formed by boring a hole 8 in the casting 1 in such a manner that it cuts away one 110

of the elbows or angular bends of the tube 2. The outer end of the hole 8 is closed by a plug 9. In the particular illustration given, also a hole constituting an oil conduit 10 is 5 bored into the casting 1 and through the intermediate portion of the tube 2. A valve-equipped bushing 11 is shown as screwed into the lower extremity of the conduit 10. Also, as shown, the numeral 12 indicates a 10 valve-equipped conduit bored into one end of the casting 1 and opening into the hole 5 of the said casting. This latter feature, however, constitutes no part of the present invention, and, in fact, it will be understood 15 that the particular casting with valves in the arrangement illustrated, has been described only for the purpose of illustrating one of the many ways in which my invention can be utilized.

20 It is thought to be evident that by the use of the conduit forming tube cast into the body of the casting, it becomes a very easy matter to form accurate smooth walled conduits on any and all desired lines, and, in fact, makes it an easy matter to form intricate tortuous conduits as it does to form 25 straight or more simple conduits. In fact, it makes it possible to form conduits which are of such a character that they could not 30 otherwise be formed.

What I claim is:

1. The process of constructing fluid conduits in castings, which consists in placing

the body of a tube in the cavity of a mold, in casting the body of the casting around 35 said tube, and in thereafter boring into said casting a hole that cuts into said tube and affords a valve seat or the like.

2. The process of constructing fluid conduits in castings which consists in forming 40 a tube to the desired contour of the conduit, in applying a tube anchor to at least one end of said tube, in placing the said tube in the cavity of the mold with the tube anchor embedded in the mold, and in casting the 45 body of the casting around said tube, and in thereafter boring into the said casting, holes intersecting and severing the said tube to afford valve seats, or the like.

3. The process of constructing tortuous 50 fluid conduits in castings, which consists first in forming a tube to the contour of the desired conduit, in placing the said tube in the cavity of the mold, in casting the body 55 of the casting around said tube, and in thereafter boring holes into said casting at points intersecting and cutting away angular portions of said tube to thereby afford valve seats or the like.

In testimony whereof I affix my signature 60 in presence of two witnesses.

JAMES F. CORVIN.
